United States Patent Office

RUFUS TROWBRIDGE, OF WATERLOO, IOWA.

Letters Patent No. 66,267, dated July 2, 1867.

SHOVEL-PLough.

The Schedule referred to in these Letters Patent and making part of the same.

TO ALL WHOM IT MAY CONCERN:

Be it known that I, RUFUS TROWBRIDGE, of Waterloo, in the county of Blackhawk, in the State of Iowa, have invented a new and useful Improvement on a Shovel-Plough; and I do hereby declare that the following is a full, clear, and exact description of the construction and operation of the same, reference being had to the accompanying drawings.

I construct my shovel-plough in any of the known forms, and attach thereto as many shovels as desired. I make my shovel for double-shovel ploughs about eleven inches long, seven inches wide at the top, and six and three-quarter inches wide at a point about two-thirds of the distance from the top downward, at which latter point I make each edge of a gentle and uniform curve until these curves meet at the lower extremity forming the point of the shovel. This point I curve slightly forward in the form of many shovels now in use. I make my shovel of two plates, the face of cast-steel three-eighths of an inch thick in the main. I weld to this on the back side an iron plate one-quarter of an inch thick, and make both to come to a sharp edge about one-third of the distance from the lower end upward. I then make a groove in the face three-eighths of an inch deep, and extending about two-thirds of the length of the shovel from the top, and within about one-fourth of an inch on each side, leaving the steel on three sides of the groove projecting three-eighths of an inch above the iron plate. These steel projections I groove under a little from the inside. I next make two holes in the iron plate for bolting the shovel to the standard, and countersink these holes in the common manner to receive the heads of bolts on a plane surface with the plate, and fit these bolts in their places. I then fit a plate of glass three-eighths of an inch thick into the grooves spoken of, leaving it on a plane surface with the steel plate. I make my standard in the ordinary manner, except at the upper extremity of the shovel I make it to project out so as to be on a plane surface with the face of a shovel, which projection serves to keep the glass plate in its place. The glass and the form of the standard have a great tendency to prevent the dirt from adhering to the shovel, and the glass prevent the wear to a great extent.

What I claim as my invention, and desire to secure by Letters Patent, is—

The combination of a flat glass plate to the face of the share of shovel-ploughs, substantially as specified.

RUFUS TROWBRIDGE.
